UNITED STATES PATENT OFFICE.

THOMAS NELSON MARTIN, OF OMAHA, NEBRASKA.

DESIGN FOR A CHECK-HOOK.

SPECIFICATION forming part of Design No. 29,382, dated September 20, 1898.

Application filed August 16, 1898. Serial No. 688,948. Term of patent 14 years.

To all whom it may concern:

Be it known that I, THOMAS NELSON MARTIN, a citizen of the United States, residing at Omaha, in the county of Douglas and State of Nebraska, have invented a new and original Design for a Check-Hook, of which the following is a specification.

This invention relates to a new and original design for a check-hook; and it has for its object to provide a design of this character which shall be both useful and ornamental.

The leading feature of the design resides in a check-hook formed with an ovoidal-shaped hook member having an arched upper side tapering in width toward its extremity, and a widened lower base portion formed near its extremity with a substantially inverted-V-shaped angular projection, and an arm-piece abutting at its lower end against one of the inclined faces of said angular projection, and extending across the space between the opposite terminals of the hook member and intersecting the terminal of said arched upper side, said arm-piece having a laterally-disposed circular enlargement at its upper end.

In the drawings, Figure 1 is a perspective view of a check-hook embodying the herein-

described design. Fig. 2 is a side elevation thereof.

Referring to the drawings, the numeral 1 designates the hook member of the check-hook, which is of an approximately ovoidal shape, having an arched upper side 2, tapering in width toward its extremity, and a widened lower base portion 3, formed near its extremity with an angular projection 4 of a substantial inverted-V shape. An arm-piece 5 intersects the terminal of the upper side 2 of the hook member and abuts at its lower end against one of the inclined faces of the angular projection 4. The said arm-piece 5 is formed with a laterally-disposed circular enlargement 6 at its upper end and a longitudinally-concaved outer side 7.

What I claim is—

The design for a check-hook herein shown and described.

In testimony that I claim the foregoing as my own I have hereto affixed my signature in the presence of two witnesses.

THOMAS NELSON MARTIN.
